UNITED STATES PATENT OFFICE.

CHARLES CAMPBELL AND DUNCAN CAMPBELL, OF PHILADELPHIA, PENNSYLVANIA.

DESIGN FOR A PHOTO FRAME OR STAND.

53,704.

Specification for Design.

Patented Aug. 19, 1919.

Application filed May 13, 1919. Serial No. 296,934. Term of patent 14 years.

To all whom it may concern:

Be it known that we, CHARLES CAMPBELL and DUNCAN CAMPBELL, subjects of the King of Great Britain, residing at Philadelphia, in the county of Philadelphia and State of Pennsylvania, have invented a new, original, and ornamental Design for a Photo Frame or Stand, of which the following is a specification, reference being had to the accompanying drawing, forming a part thereof.

The figure is a front elevation of the photo frame or stand, illustrating our new design. We claim:

CHARLES CAMPBELL.
DUNCAN CAMPBELL.
